**LIQUOR OR WINE BOTTLE OPENER
SEAL CUTTER**

John W. Svalgaard, Minneapolis, Minn.

Application July 13, 1954, Serial No. 442,961

1 Claim. (Cl. 30—1.5)

This invention relates to a device for cutting the seals of liquor or wine bottles to facilitate the opening of such bottles.

An important object of the invention is to provide an opener of this character embodying a yieldable split ring adapted to be pressed over the seal of a bottle, the split ring having a seal cutting blade adapted to move through the seal cutting the seal as the split ring is rotated permitting the cap to be removed from the bottle.

Still another object of the invention is to provide a device of this character constructed of plastic material of a size to receive a name or advertising material advertising the goods with which the opener may be used.

Referring to the drawings,

Figure 1 is a fragmental elevational view illustrating a seal cutter constructed in accordance with the invention, as positioned for cutting the seal of the bottle.

Figure 2 is a plan view thereof.

Figure 3 is a view illustrating the closure of the bottle as removed with the seal cutter in place thereon.

Figure 4 is a perspective view of one form of seal cutter.

Figure 5 is a perspective view of a modified form of seal cutter.

Referring to the drawing in detail, the reference character 5 indicates a conventional screw cap of a liquor or wine bottle, and the reference character 6 indicates the usual seal which is positioned over the cap and a portion of the neck 7 of the bottle sealing the cap in position.

The reference character 8 indicates the seal cutter forming the subject matter of the present invention, and as shown, the seal cutter in its preferred form is constructed of a length of plastic material formed into a yieldable split ring indicated by the reference character 9. The

2

reference character 10 indicates a blade which extends inwardly from one end of the split ring, as better shown by Figure 2 of the drawing, the blade being designed to contact the seal 6, at the point of contact between the 5 cover 5 and mouth of the bottle. Formed as an integral part of the ring 9 and disposed directly over the cutting blade 10 is an enlargement 14 which affords means for effecting rotation of said ring while pressure is being directed to the ring to cut the seal. Thus it will be 10 seen that by pressing the end of the split ring inwardly, the blade 10 will cut the seal at the point of contact between the cap and mouth of the bottle as the split ring is rotated around the cap. The cap may now be readily removed.

In the form of the invention as shown by Figure 5 of the drawing, the split ring which is indicated by the reference character 11 is formed of a length of yieldable wire material with one end formed into a loop 12. The cutting blade indicated at 13 is formed on the loop 12 and extends inwardly so that when the split ring is positioned over a cap to cut the seal, the blade 13 will fall directly opposite to the point of contact between the cap and mouth of the bottle, so that when the device is rotated, the blade 13 will sever the seal and permit the cap to 25 be readily removed.

From the foregoing it is believed that the construction and operation of the cutter will be obvious, and that a further description and disclosure of the device is unnecessary.

Having thus described the invention, what is claimed is:
A bottle closure seal cutter comprising a split yieldable ring member of a diameter to substantially encircle the mouth of a bottle and adapted to be fitted around the seal of a bottle, a blade extending inwardly from said ring member adjacent to one end thereof, said blade adapted to cut the seal of the bottle as said blade is pressed into contact with said seal during rotation of said split ring member, and an enlargement formed on the outer surface of said split ring directly over said blade providing a finger piece for effecting rotation of said split ring.
